INVENTOR,
DENNIS M. ANDERSON
By Shigley & Harvey, ATTORNEYS

UNITED STATES PATENT OFFICE.

DENNIS M. ANDERSON, OF COLUMBUS, OHIO.

DRAIN SHELF.

Application filed October 16, 1922. Serial No. 594,851.

To all whom it may concern:

Be it known that I, DENNIS M. ANDERSON, a citizen of the United States of America, residing at Columbus, in the county of Franklin and State of Ohio, have invented certain new and useful Improvements in Drain Shelves, of which the following is a specification.

My present invention relates generally to 10 glassware and dish drains, and more particularly to a drain shelf for use in connection with and supplemental to a kitchen sink and the like, my object being the provision of a small sanitary drain shelf which may be 15 utilized in connection with a kitchen sink and the like in such manner as to drain into the sink, and which may be easily and quickly detached when it is not desired for use.

20 In the accompanying drawing which illustrates my present invention and forms a part of this specification,

Figure 1 is a front view illustrating the practical application of my invention,

25 Figures 2 and 3 are respectively a detail front view and side view thereof,

Figures 4 and 5 are respectively a longitudinal section and a transverse section therethrough,

30 Figure 6 is a top plan view thereof, Figure 7 is a detail perspective view of the wall support or bracket, and

Figure 8 is an enlarged fragmentary vertical section through a portion of the device and the wall bracket supporting the same.

Referring now to these figures I have shown in Figure 1 a conventional type of sink 10 such as commonly used in the kitchens of homes, having a drain extension 11 above and supplemental to which my present proposed drain shelf is adapted for use in such manner as to drain downwardly into the sink 10 or upon its drain extension 11, my improved drain shelf being generally indicated at 12 in Figure 1, and being as shown particularly in Figures 2 to 6 inclusive, preferably stamped or pressed from a single piece of material which is thereafter coated or surfaced in such a way 45 as to present a non-absorbing exterior permitting the drain shelf as a whole to be readily cleaned and maintained in a sanitary condition at all times.

The drain shelf as proposed by my inven-

tion is formed with a back plate 13 and a 55 base 14, the latter outstanding from the lower portion of the back plate and sloping from one end to the other, either with a plain upper surface or with drain grooves 15, the latter if present converging toward 60 a downwardly opening drain 16 located adjacent to the lower end of the base and in practice opening above either the sink 10 or its extension 11 as shown in Figure 1.

The base may be provided with a 65 surrounding rim 17 for the better support of glassware or small dishes to prevent the latter from falling off, and the back plate has means providing for its detachable support so that it may be easily placed in position 70 when the shelf is to be used and as quickly removed when its use is no longer desirable, in order that it may be stored out of the way.

For the above purpose the bracket has a 75 rearwardly curved peripheral flange 18 and this flange is provided at the upper edge of the back plate with depending lugs 19 adapted to enter pockets 20 formed in the length of an attaching bar or bracket 21 80 adapted to be secured by any suitable fastening members to a wall 22 of the sink, the fastening means employed being of various natures depending upon the particular character of the wall.

It is thus obvious that by virtue of its rearwardly curved flanges the back plate entirely conceals the supporting bracket from view when the drain shelf is in the effective position and that for the support 90 of the drain shelf all that is necessary is to shift the lugs 19 downwardly into the pockets 20 of the bracket. To remove the drain shelf all that is necessary is to lift these lugs out of the pockets and the drain 95 shelf can then be stored away leaving the space above the sink 10 and its extension 11 entirely free of obstruction.

I claim:

1. A glassware and dish drain shelf having a back plate and a base plate the latter sloping from one end to the other and provided with a downwardly opening drain adjacent to its lower end, a wall bracket having pockets therein, and lugs depending 100 from the upper portion of the back plate for removable disposition in said pockets.
2. A glassware and dish drain shelf hav-

ing a back plate and a base plate the latter sloping from one end to the other and provided with a downwardly opening drain adjacent to its lower end, a wall bracket having pockets therein, said back plate having a rearwardly curved peripheral flange entirely therearound, and lugs depending

from the upper portion of the flange for removable disposition in the pockets of said bracket.

In testimony whereof I have affixed my signature.

DENNIS M. ANDERSON.
